UNITED STATES PATENT OFFICE.

HORACE A. YOUNG, OF WORCESTER, MASSACHUSETTS.

WIRE-ROD-REELING MACHINE.

SPECIFICATION forming part of Letters Patent No. 369,307, dated August 30, 1887.

Application filed May 5, 1887. Serial No. 237,170. (No model.)

To all whom it may concern:

Be it known that I, HORACE A. YOUNG, of Worcester, in the county of Worcester and State of Massachusetts, have invented certain new and useful Improvements in Wire-Rod-Reeling Machines; and I do hereby declare that the following is a full, clear, and exact description of the same, reference being had to the accompanying drawings, forming a part of this specification, and in which—

Figure 1 represents a top or plan view of my aforesaid improved wire-rod-reeling machine. Fig. 2 is a front side view of the upper end of said machine, looking in the direction indicated by the arrow in Fig. 1; and Fig. 3 is a central vertical section of the whole machine, taken on line *a a*, Fig. 1, looking in the direction of the aforesaid arrow in said figure.

20 My invention relates to vertical reeling-machines for coiling wire rods, and more particularly to improvements in the wire-rod-reeling machines shown and described in my previous application for a United States patent filed January 31, 1887, and bearing serial number 226,026.

Said invention comprises improvements in the construction and arrangement of the upper portion or reel of said machine, herein-after more fully specified.

30 Following is a full, clear, and exact description of said improvements, reference being had to the accompanying drawings.

The parts for supporting and operating the reel *A* being shown like those in my said previous application, it is deemed unnecessary to give a full and detailed description thereof to make clear the nature and purpose of my present improvements.

40 The parts *b* represent the supporting framework having ways formed in the vertical inner sides, *b'*, thereof, in which a frame or carriage, *c*, is fitted to slide up and down, said carriage being elevated by means of the pistons *d d*, operated by steam or hydraulic power, and lowered by the weight thereof and parts supported thereon when the upward pressure is removed. Carriage *c* has fitted centrally thereto, and also supports in a step, 45 *c'*, at the bottom, a hollow shaft or sleeve, *e*, having a circular plate, *e'*, formed upon or se-

cured horizontally upon its upper end, the purpose of which will be later described.

The main driving-shaft *f* of the machine passes up through the aforesaid carriage *c* and sleeve *e*, and is supported at the bottom in a step, *f'*, constituting a part of bearing *g*, in which one end of the horizontal shaft *h* turns. The latter shaft may be turned in any well-known way, and power is transmitted 55 therefrom to drive the vertical shaft *f* through the bevel-gears *i j*, secured to said shafts *f* and *h*, respectively.

The shaft *f* has rotary movements only, whereas the sleeve *e* is fitted to turn with said 65 shaft and also to slide up and down thereon with carriage *c*, and said carriage has only vertical movements, the purposes of which movements will be hereinafter more fully explained in a brief description of the operation 70 of the whole machine.

We now come to the parts of the machine to which my improvements relate.

To the upper end of shaft *f* is secured a cylinder or drum, *k*, having a series of vertical 75 slots, *k'*, (eight in this instance,) in its outer surface, formed between the radially-projecting flanges *k''*, and upon the circular plate *e'*, at or near the outer edge thereof, are formed or secured a series of upwardly-projecting 80 arms, *l*, which extend up into the aforesaid vertical slots *k'*. Said arms *l* are each provided with a pair of gears, *m n*, and also with a cap or hood, *l'*, over each pair of gears, in like manner to the machine shown in my previous application; but instead of providing 85 both gears of each pair with an arm or spoke, as shown in said application, only the outer small gears or pinions, *n*, are in this instance provided with such arms or spokes *o*, and instead of operating the gears by connection with the plate corresponding to plate *e'*, or by a rack formed on the outer surface of the cylinder, I employ in my present construction a link, *p*, for connecting each large inner gear, 90 *m*, with one of the flanges *k''* on the cylinder or drum *k*, as shown in the drawings. By the use of said flanges *k''* it is obvious that the inner row of arms or spokes shown in my other application may be dispensed with, the wire 95 rods being coiled between the outer edges, *k''*, thereof and the arms or spokes *o* on the pin-

ions n , said rods being laid on top of the arms l in continuous coils around the outside of the drum.

The outer edges, k^3 , of flanges k^2 are preferably made slightly converging toward the top, corresponding to the taper of the arms o , to facilitate the operation of elevating the finished coil to the top of the machine preparatory to its removal therefrom.

10 The construction of the reel, as hereinbefore described, whereby the inner row of movable arms may be dispensed with, constitutes the essential feature of my improvements. By said construction I am enabled to effect the 15 same result as by the machine previously referred to at a considerably less cost in manufacturing the same.

If desired, the drum k may be made with a plain cone-shaped outer surface, (without the 20 vertical flanges k^2), and vertical slots formed therein to receive the inner gears, m , and links p , or otherwise similarly made, without departing from the principle of my invention. I prefer, however, the construction shown in 25 the drawings.

The operation of the whole machine, in connection with my improvements, may be briefly summed up as follows: Assuming that the carriage c and parts supported thereby are in 30 their lowest positions with the arms o elevated, as shown by full lines in Figs. 2 and 3, the wire rod is now deposited upon the reel, as usual, and coiled over the arms l between the drum k and the aforesaid arms o . Upon the 35 coil being completed the reel is stopped and carriage c elevated, thereby also elevating the sleeve e and parts connected therewith into the positions indicated by dotted lines in Fig. 3, with the tops of arms l upon a level with 40 the top of drum k and the arms or spokes o swung down into a reverse vertical position. Said arms o are thus swung down by the partial rotation of the inner gears through the connections previously described, and the consequent rotation of the smaller outer gears to 45 which the arms are secured. Although the

gears are shown as being provided with teeth only on portions of their peripheries, and the gears so made as to swing arms o into a reverse vertical position, as before stated, I do not 50 limit myself thereto, the main purpose being to swing said arms down out of the way, so as to remove the coil horizontally from the top of the reel. Said coil having been elevated, as aforesaid, may thus be removed by any suitable and convenient means. Said means, as well as the means for elevating and starting the machine, not constituting a part of my invention, it will be unnecessary to either illustrate or describe the same.

Having described my said invention, what I claim therein as new, and desire to secure by Letters Patent, is—

1. In a vertical reeling-machine for coiling wire rods, a central rotating drum or cylinder 65 mounted on the upper end of the main vertical driving-shaft and adapted to hold the inside of the coil in position, in combination with an outer circular row of movable arms, the supports thereof consisting of a series of radial 70 arms projecting up from a plate having vertical movements, and means operatively connected with said drum and supporting-arms, whereby, when the latter are moved up, the arms or spokes above referred to are swung 75 down out of the way of the coil, and when moved down are elevated to hold the outer side of said coil, substantially as shown and specified.

2. The combination of drum k , mounted on 80 the upper end of the central vertical shaft, f , with links p , gears m , the latter fitted to turn on arms l , arms or spokes o , secured to gears n , said arms l , and means for supporting and moving the same up and down to elevate the 85 coil and at the same time operate arms or spokes o , substantially as and for the purpose set forth.

HORACE A. YOUNG.
